The image shows four staves of musical notation for a band or orchestra. The notation is a mix of rhythmic patterns and note heads, likely representing a transcription of the piece. The staves are in common time and use a variety of note heads, including x, 4, and 2, with corresponding stems and rests. The music is divided into measures by vertical bar lines.

UNITED STATES PATENT OFFICE.

ERNEST VON HEERINGEN, OF PICKINSVILLE, ALABAMA.

MUSICAL NOTATION.

Specification of Letters Patent No. 6,528, dated June 12, 1849.

To all whom it may concern:

Be it known that I, ERNEST VON HEERIN-
GEN, of Pickensville, in the county of Pick-
ens and State of Alabama, have invented
5 certain new and useful Improvements in
Musical Notation, of which the following is
a full, clear, and exact description, refer-
ence being had to the accompanying scores,
which show the difference between the old
10 method and my improved notation.

The first portion of my invention is de-
signed to enable beginners to acquire the
fingering of any keyed instrument without
numbering the notes on the score, as is usu-
ally done. To accomplish this I make all
15 notes to be played by the thumb of a circular
form thus , which may be cued in the
usual manner to show the length of the note;
and to direct the proper finger to the re-
20 maining notes I divide this thumb note into
four portions by a horizontal and vertical
line crossing each other within the circle
thus ; each of those portions when taken
25 by itself will form a distinct character, one
of which corresponds with each finger of
the hand, the lower left hand one being
touched by the first finger, the upper left
hand one by the second finger, the up-
30 per right hand quarter by the third fin-
ger, and the lower right hand one by the
fourth finger. I prefer the circular form to
others, but it is evident that any geometri-
35 cal figure which can be divided into four
distinct portions will answer the purpose,
thus a square placed diagonally on the
lines might be used to denote the thumb,
and the four triangular quarters 40 The second portion of my improvement is
in the method of counting the musical in-
tervals or notes, taking the chromatic scale,
instead of the diatonic for my base. In the
usual method the notes are numbered from
45 1 to 7 in the order in which they occur in
the diatonic scale skipping the half tones,
which fall between the full notes, thus C
being numbered 1; D is numbered 2; E, 3;
F, 4; G, 5; A, 6; and B, 7. In my method
50 C being numbered 1 C# will be 2; D, 3;

D#, 4 &c. and the two methods will com-
pare as follows:

	Usual method.	Improved method.	
C	1	1 0	55
C#		2 0	
D	2	3 0	
D#		4 0	
E	3	5 0	
F	4	6 0	
F#		7 0	60
G	5	8 0	
G#		9 0	
A	6	10 0	
A#		11 0	
B	7	12 0	65
C	1	1 0	

Any appropriate name or letter may be
given to each of these twelve notes but as the
syllables do, dee, ray, ree, me, fa, fee, sol,
see, la, lee, pa, have proved excellent in teach-
ing vocal, and instrumental music combined,
I prefer to retain them; and thus all the
confusion and trouble experienced by a be-
ginner, in mastering the difficulties, and dis-
tinctions between sharps, flats and naturals
is entirely avoided. In the third portion of
my improved method of notation, the exact
sound of the note whether sharp, flat, or
natural is shown by the musical characters
themselves without the assistance of chro-
matic signatures. This is accomplished by
making all the characters which represent
the natural sounds, or those usually denoted
80 by the letters C, D, E, F, G, A, B, of one
uniform color, (and making those charac-
ters which are to represent the sharps or
flats usually denoted by the letters C#, D#,
F#, G#, or D^b, E^b, G^b, A^b, and B^b of an
other uniform color, distinct from that of
the natural sounds). Thus the color of the
first may be white, corresponding with the
white keys of a piano or organ, and the
color of the second may be black correspond-
ing with the black keys of the same instru-
ments. If then the note placed in the third
space of the treble stave be colored white,
it will represent the sound usually called C
(C natural), while if the note in the same
space be colored black, it will represent a 90
95
100

sound raised one half tone higher or that musical sound commonly called C[#] or D^b, (C sharp or D flat); the same will be the case with the other notes of the stave, thus 5 if the note on the uppermost line of the treble stave be white it represents the musical sound commonly called F (F natural) and if it be black it will represent F[#] (F sharp) or G^b (G flat) being one half tone 10 higher than F (F natural); and the characters on the stave will appear as in AIV of the score hereunto annexed. It is evident that any other colors might be used, but these are most convenient both for 15 printing and instruction. The value of the notes indicated by the cue attached to them, will be the same as those in the ordinary notation, the only difference being in the head.

20 The advantages of this improved notation will be evident to any one who has had to contend with the difficulties incidental to the old system. First, the fingering of any piece of music is clearly shown by the characters 25 themselves without requiring any aditonal figures above or below the stave to denote what finger is to be applied to each key. Second, all the confusion arising from calling sharps and flats by the same names 30 as the naturals intervening between them is avoided. Each of the twelve names or letters will represent a distinct musical sound, which will not be confounded with the preceding or succeeding one. Third, chromatic 35 signatures either at the commencement of the stave or at accidental sharps or flats within the stave are entirely done away with, and much less labor or expense is required to write or print music, and if chromatic 40 signatures are desired for the purpose of transposition, no more than five black notes are needed to express any number of flats or sharps. Fourth, the color of the notes corresponds with that of the keys of 45 the piano, organ, eolian, &c., it is therefore extremely easy to find the correct note on

any such instrument, when the white notes represent the white keys, and the black notes the black keys. Fifth, music written in this manner is much easier to read because the 50 eye does not become confused by the uniformity in the color of the notes. Sixth, pupils can become performers in less than half the time required by the old system. Seventh, pupils are encouraged by it to attempt 55 pieces that it would be impossible for them to play if written in the old method, where the mind is not only required to recollect the key of the instrument corresponding with the note of the written music, but also 60 to recollect the signature at the end of the stave and the peculiar method of fingering. Eighth, all old music, or music written in the old style is easily transposed into this new system (the piece No. 3 that accompanies 65 this specification having been transposed by one of my pupils.)

Having thus described my improved notation, what I claim therein as new and desire to secure by Letters Patent, is—

1. The arrangement of distinct characters to denote the fingering of music, made and arranged substantially in the manner herein described.
2. Giving the twelve musical intervals distinct names so that the use of the words flat and sharp is entirely avoided, and with them all the confusion naturally arising in the mind of a beginner.
3. Representing the sounds usually called natural by one uniform color, and those commonly called flats and sharps by another uniform color so that they may be distinguished from each other by a mere inspection of the musical character representing the note without the use of chromatic signatures.

ERNEST VON HEERINGEN.
